UNITED STATES PATENT OFFICE.

THOMAS B. HUESTIS, OF BOSTON, MASSACHUSETTS, ASSIGNOR OF TWO-THIRDS TO WILLIAM H. STANLEY AND HERDMAN MCKAY, OF SAME PLACE.

MACHINE FOR MAKING TOE-CALKS FOR HORSESHOES.

SPECIFICATION forming part of Letters Patent No. 508,544, dated November 14, 1893.

Application filed August 10, 1893. Serial No. 482,801. (No model.)

To all whom it may concern:

Be it known that I, THOMAS B. HUESTIS, of Boston, in the county of Suffolk and State of Massachusetts, have invented a new and useful Machine for Making Toe-Calks for Horseshoes, of which the following is a specification.

It is well known to those skilled in the art to which this invention relates, that the short piece of steel which constitutes the toe calk is provided with a spur at one end which is driven into the heated shoe and serves to hold the calk in its proper place until the calk and shoe are welded together.

15 The spur has heretofore been forged upon one end of the calk by hand and the object of this invention is to provide a machine for forming the spur and severing the calk from its stock with the expenditure of little time and labor.

One feature of the invention is the combination of a support for the stock from which the calk is made; a pair of dies acting upon adjacent sides of the stock and means for preventing movement of the stock during the action of the dies.

Other features will appear hereinafter.

In the drawings: Figure 1 is a diagrammatic view of the dies, the support and stop for the stock from which the calk is made; Fig. 2 a detail of the finished calk; Fig. 3 a side view of the machine; Fig. 4 an end view of the same looking in the direction of arrow 4, Fig. 3. Fig. 5 is a view of the opposite end; Fig. 6 a plan view; Fig. 7 a partial section on line 7-7 of Fig. 6; and Figs. 8 and 9 details of two of the cams.

The driving shaft *a* has a pulley *a'* and pinion *a''* driving gear *b'* of cam shaft *b* which is supported by hangers *c'* *c''* from bed *c*. A frame *d* is secured upon bed *c* and supports the fulcrums of levers *e*, *f*, *g*, *h*, and *i*. The periphery of cam *b''* moves lever *g* which carries the adjustable clamp *g'*, link *g''* and pawl *g'''* presently to be described. A roll *b''* on cam *b''* moves lever *i* which carries shears *i'* by which the calk is severed from the stock. Cam *b''* has four swells and operates lever *e*

on which is mounted the movable rest *e'*; cam *b''* has four swells of increasing radii to impart a greater thrust to die *f'* upon each movement toward the rest *e'*. Cam *b''* is a disk with the swells *b''* upon its face actuating lever *h* which carries die *h'*. Levers *g* and *h* are retracted by springs *s* and *s'* and levers *e* and *f* are connected below their fulcrums by coiled spring *s''* to maintain the levers in contact with their cams. Frame *d* has an upright *d'* which supports the anvil *k* and a stop or guide *k'* which overhangs anvil *k* and is secured by bolts *k''* which also secure anvil *k* in place. A plate *i''* is supported by bolts *i'''* upon upright *d'* and this plate constitutes the second member of the shear *i'*. A plate *m* slides in a groove on the upright *d'*, and is held in place by pin *m'* and retracted by spring *m''* when released by pawl *g'''* after the pawl has been actuated by clamp lever *g* to displace the finished calk from the anvil.

The calks are usually made from a strip of steel of the proper shape and this strip is laid upon anvil *k*. The mechanism being in operation, the clamp *g'* descends and holds the strip securely upon the anvil. The rest *e'* and die *f'* then move together, die *f'* pressing the material out from the end of the steel strip. The rest *e'* and die *f'* then separate and die *h'* acts upon the end of the strip to point the spur *u*. The rest *e'* and die *f'* acts four times, die *f'* entering the steel a little farther at each stroke, and die *h'* acting three times. When these dies have completed their work shears *i'* act to sever a sufficient length from the strip for a calk and as lever *g* recedes, pawl *g'''* pulls plate *m* with it, pushing the calk off of the anvil whence it falls into a proper receptacle underneath the machine. A stationary cam *m''* raises pawl *g'''* and plate *m* returns to its first position.

It will be observed that levers *f* and *h* are fulcrummed at some distance from the anvil and this is a feature of my invention because the dies are thus caused to travel downwardly when acting upon the material of the calk and the spur is thereby more readily drawn

down from the body of the calk instead of relying entirely upon the inclination of the faces of the dies to effect their purpose.

What I claim is—

1. In combination a moving rest; a clamp and a pair of dies acting respectively upon the side and end of the bar, substantially as and for the purposes described.
2. In combination a clamp; a moving rest; a pair of dies acting respectively upon the side and end of the bar and a severing device, substantially as and for the purposes described.
3. In combination, an anvil; a clamp; a movable rest and die opposed to each other and

operating simultaneously, the thrust of the die varying in extent; and another die moving at an angle to the first die and alternately with it; as and for the purposes set forth.

4. In combination, a pair of dies operating at an angle to each other; an anvil supporting the stock; a clamp, a rest opposed to one of the dies, and mechanism substantially such as is described, for actuating the dies alternately.

THOMAS B. HUESTIS.
